UNITED STATES PATENT OFFICE.

HARRY S. FOLGER, OF CHICAGO, ILLINOIS.

TYPE-HOLDER.

SPECIFICATION forming part of Letters Patent No. 723,665, dated March 24, 1903.

Application filed April 3, 1902. Serial No. 101,144. (No model.)

To all whom it may concern:

Be it known that I, HARRY S. FOLGER, a citizen of the United States of America, and a resident of Chicago, county of Cook, and 5 State of Illinois, have invented certain new and useful Improvements in Type-Holders, of which the following is a specification.

My invention relates to type-holders, and has for its object improvement in such holders. More particularly, the invention relates to holders for rubber type, though I make it also to hold metallic type by putting rubber or other yielding material under the type and on the "leads" or line-dividing plates. The 15 present type-holder differs from other holders in that the type-holding channels are composed of line-dividing plates which are adjustable, so that they can accommodate type of different sizes, which plates are held by 20 bars or otherwise from falling out of the holder.

In the accompanying drawings, Figure 1 is a perspective view showing a holder arranged as a hand-stamp for either rubber or metallic 25 type. Fig. 2 is a plan. Fig. 3 is an end elevation. Fig. 4 is an enlarged detail showing the construction of the line-dividing plates. Fig. 5 is a section on line 5-5 of Fig. 4. Fig. 6 shows the construction of the line-dividing 30 plates when the type-holding frame is wide enough to permit of its use; and Fig. 7 is a perspective view of the form of holder used with a press, the type being omitted.

In the said drawings, A is a type-holding 35 frame consisting of a metallic plate having opposite edges turned up to form the flanges A'. Connecting the ends of opposite flanges are the bolts B. In narrow holders, like that of Fig. 1, these bolts are secured by nuts B', 40 but in wide holders, like that of Fig. 7, they may be simply rivets. Mounted on the bolts B are a series of line-dividing plates P, which are provided with a rubber covering P' in 45 holders intended to hold metal type either part of the time or all of the time. In holders intended only for rubber type the covering P' may be omitted. In narrow holders the plates P are provided with holes P², through which the bolts B pass, the bolts being removable for the purpose of permitting 50 the removal of the plates. In wide holders this hole becomes the notch P³ of Fig. 6.

The reason for this difference is that in holders having a considerable distance between the flanges A' the plates P may be inserted or 55 removed by turning them to an angle with the flanges sufficient to permit the extreme ends of the plates to clear the bolts B, while holders having the flanges near together do not permit a sufficient inclination of the 60 plates to allow them to be removed. The question of hole P² or notch P³ is therefore largely a question of size of holder, and the question of whether B is a bolt or a rivet depends upon the construction of the plates P. 65

In holders intended for the use of metal as well as rubber type there is placed a cushion A², of rubber or other yielding material, under the type T close to the lower edges of the line-dividing plates P. In one of the 70 flanges A' are screws S, which bear against a plate P⁴, similar to the plates P, but preferably heavier and without a rubber covering P'. When the type T are placed in the holder and the screws S are tightened up, a 75 comparatively light pressure serves to hold the type in place, because each line of type is held on both sides by a line-dividing plate, and these plates are in turn held by the rods or bolts B. There is consequently no tendency for the type to get off of their feet, and to secure this result to the best advantage the plates P are made to fit the bolts B pretty closely. It will be obvious that it is 80 not essential to use bolts B of the character 85 shown. The ends of the plates P might be held in grooves or in any other convenient manner. What is essential is that they be adjustable to accommodate type of different sizes and that they be held so that they will 90 in turn hold the type from rising off of their feet.

What I claim is—

1. In a type-holder, a metallic plate having opposite edges turned up to form flanges, removable bolts connecting the opposite flanges near their ends, line-dividing plates supported by and guided on said bolts, and screws located in one of said flanges between said bolts and arranged to press said plates 100 toward each other so as to clamp type within said holder.

2. In a type-holder, a frame provided with flanges, a yielding cushion supported in said

frame between its flanges, guides connecting the ends of opposite flanges, line-dividing plates held by said guides and movable over the surface of said cushion so as to form type-holding channels of variable widths, and means for clamping said plates upon type in said channels so as to firmly hold such type in place with their feet on said cushion.

3. In a type-holder, a frame provided with flanges, bolts connecting said flanges, line-dividing plates provided with coverings of

yielding material, said plates being held by and adjustable on said bolts, and screws located in one of the flanges of said frame and adapted to press said plates upon type held in said holder.

Signed at Chicago, Illinois, this 26th day of March, 1902.

HARRY S. FOLGER.
